H. C. BOEDICKER

NEGATIVE GLASS AND MEANS FOR HOLDING SAME

Original Filed Oct. 18, 1919

FIG. 1

FIG. 2

INVENTOR
HERMAN C. BOEDICKER
BY C. E. Nichols
ATTORNEY

UNITED STATES PATENT OFFICE.

HERMAN C. BOEDICKER, OF NEW YORK, N. Y.

NEGATIVE GLASS AND MEANS FOR HOLDING SAME.

Application filed October 13, 1919, Serial No. 332,082. Renewed January 6, 1923.

To all whom it may concern:

Be it known that I, HERMAN C. BOEDICKER, a citizen of the United States, and a resident of New York, in the borough of Manhattan and State of New York, have invented certain new and useful Improvements in a Negative Glass and Means for Holding Same, of which the following is a specification.

10 One object of my invention is to provide an improved form of negative glass of such style that it may be securely held by means positioned entirely back of the front surface of the negative glass.

15 Another object is to provide improved means for holding a negative glass from a position back of its front surface.

With these and incidental objects in view, the invention consists of certain novel features of construction and combination of parts, the essential elements of which are hereinafter described with reference to the drawing which accompanies and forms a part of this specification.

25 In the drawing, Figure 1 is a fragmentary sectional detail taken on the line 1—1, Figure 2; Figure 2 is a front view of my improved device; and Figure 3 is a longitudinal, sectional view of the clamping means.

30 This invention relates to an improvement on the negative glass and negative box shown and described in my co-pending application, Serial Number 292,980, filed April 26, 1919, and entitled Photolitho machine.

35 As shown in Figure 1, the wall 1 of the negative box is grooved out at 2 to receive the rabbeted edge 3 of the negative glass 4.

The rabbeted edge 5 on the top of the glass is adapted to be held against the wall 6 of

40 the negative box by the lip 7 of the clamp 8.

A stop 9 mounted on the wall 10 of the negative box serves to position the glass laterally when it is placed in the negative box and it is held to the face thereof by the

45 clamp 8.

A heavy plate glass 11, similar to that shown in my co-pending application aforesaid, is mounted in the negative box in any suitable manner to help reinforce the negative glass 4 against the pressure exerted on

its face when a photolithograph machine of a type similar to that shown in the co-pending application aforesaid is used for direct contact printing.

The clamp 8 has a plunger 12 hinged at 13 to the wall 6 of the negative box, and this plunger is adapted to reciprocate in the tube 13, carrying the head 14, one end of

which is formed into the pressure lip 7. The plunger 12 has a head 15 on its free end, and the tube 13 has a closure 16, and the compression spring 17 serves to normally hold the clamp in a retracted position and thus furnishes a pressure to hold the lip 7 against the rabbeted edge 5 of the negative glass 4.

I find that this construction of negative glass is more stable than the one using a bevelled edge, as shown in my co-pending application aforesaid, and also that the clamping against the straight face of the rabbeted edge by the lip 7 holds the negative glass more securely than when I clamped on the bevelled edge of the glass.

While I have described my invention and illustrated it in one particular design, I do not wish it understood that I limit myself to this construction, as it is evident that the application of the invention may be varied in many ways within the scope of the following claims:

Claims:

1. The combination of a negative glass having two edges thereof rabbeted, a negative box having a groove positioned along one side thereof to receive one of said rabbeted edges, and clamping means supported on another face of said negative box for clamping the other of said rabbeted edges.

2. The combination of a negative glass having two rabbeted edges, a negative box having its front formed to receive the back face of said negative glass, means on said negative box to receive one of the rabbeted edges of said negative glass, and spring clamping means for clamping the other of said rabbeted edges, to draw the back surface of said negative glass securely against the front of said negative box.

HERMAN C. BOEDICKER.
